UNITED STATES PATENT OFFICE

2,561,605

DOOR

Hugh W. Bascom, Panora, Iowa

Application August 24, 1949, Serial No. 112,000

6 Claims. (Cl. 160—37)

1 My invention relates to a novel type door that is designed with a vertically arranged open portion extending substantially the length of the door and having a storage space in the door to house a glass panel and screen portion respectively, which can be individually moved into the opening when desired. This invention is in effect a combination screen and storm door and while this type of door is not new, my door contains features not found in the type door currently in use. Present type combination screen and storm doors generally consist of a permanent frame portion having an opening designed to receive a glass panel or screen member at times. These glass and screen portions are detachable and when not in use must be stored away in some place such as a basement, garage or the like where they are susceptible to damage and breakage. Consequently, each time a glass panel is interchanged with the screen portion and vice versa the respective parts must be handled and moved, thereby increasing the possibility of breakage and damage.

These objections I have overcome in my invention, the principal object of which is to provide a door with a longitudinal opening therein and which door is provided with an inner compartment adjacent the opening to house a glass panel and screen portion respectively that are capable of moving into the opening at times.

A further object of this invention is to provide a combination screen and storm door wherein the screen and glass portion can be stored within the door when not in use and which door when used as either a screen or storm door will have a one piece glass or screen portion respectively free of any separating or supporting strips visible in the portion arranged within the door opening.

A still further object of this invention is to provide a door with a longitudinal opening, and storage to house a screen and glass portion respectively that are designed to move into the opening at times and which door is refined in appearance, economical in manufacture and durable in use.

These and other objects will be apparent to those skilled in the art.

My invention consists in the construction, arrangement, and combination of the various parts of the device, whereby the objects contemplated are attained as hereinafter more fully set forth, pointed out in my claims, and illustrated in the accompanying drawings, in which:

Fig. 1 is a perspective view of my door showing the glass panel in the opening, and ready for use.

Fig. 2 is a perspective view of the lower por-

tion of this door showing a portion of the screen member in the opening.

Fig. 3 is a broken longitudinal sectional view of this door on an enlarged scale taken on the line 3—3 of Fig. 1, and

Fig. 4 is a cross-sectional view of this door on an enlarged scale taken on the line 4—4 of Fig. 1.

Referring to the drawings, I have used the numeral 10 to designate a door frame provided with the vertical longitudinal opening 11 that extends substantially the length of the frame 10. The front and back sides of the frame 10 are spaced apart to form the compartment 12 that extends from all inside marginal edges of the frame 10 to and communicating with the opening 11.

On each side of the upper and lower portions respectively of the opening 11 are the transverse slots 13, 14, 15 and 16 that have one end respectively in communication with the opening 11, as shown in Fig. 1. The slots 13 and 14 are transversely opposite each other and the slots 15 and 16 are similarly positioned.

The numerals 17 and 18 designate rod members 25 transversely arranged respectively in the lower and upper portions of the compartment 12. The numeral 19 designates an elongated glass panel arranged in a suitable frame 20 which is provided with the outwardly extending peg members 21 and 22 respectively on one side of the lower and upper portion thereof, as shown in Fig. 1. The bottom and top edges of the frame 20 respectively are provided with rod grooves 23 and 24. The glass panel 19 within the frame 20 is designed to be vertically positioned within the compartment 12 on one side of the opening 11 so that the bottom 23 and top 24 respectively are associated with the rod members 17 and 18, as shown in Fig. 3. In this position the frame 20 is laterally slidable into the opening 11 when desired.

The numeral 25 designates an elongated screen member arranged in a suitable frame 26 that is provided with the outwardly extending peg members 27 and 28 respectively on one side of the lower and upper portion thereof, as shown in Fig. 1. The bottom and top edges respectively of the screen frame 26 are provided with grooves similar to the grooves 23 and 24 on the glass panel frame 20.

The screen member 25 within its frame 26 is designed to be vertically positioned within the compartment 12 on the other side of the opening 11 opposite to the glass panel frame 20 and the frame 26 is laterally slidable into the opening 11

in the same manner as described for the glass panel member.

When this door is constructed and arranged as herein described, it will operate in the following manner: Fig. 1 shows my door with the glass panel 19 in the opening 11. The peg members 21 and 22 on the glass frame and the pegs 27 and 28 on the screen portion serve as a finger grip means to facilitate the manual sliding of the respective frames 20 and 26, as desired. The peg members are arranged on the side of their respective frames that are adjacent the opening 11. In this position, the upper peg 21 on the glass frame 20 and the upper peg 27 on the screen frame 26 are designed to be slidable within the upper slots 13 and 14. Likewise, the lower pegs 22 and 28 respectively are slidable within the lower slots 15 and 16. By this arrangement, the screen or glass portion not positioned in the opening 11 can be laterally moved into its respective portion of the compartment 12 where it does not interfere with the opening 11. Here it is in a storage place safe from damage or breakage, yet is instantly available for use without any lifting or carrying. To move any respective glass or screen member it is necessary only to grasp the respective peg grip members and laterally slide the respective frame as desired into or out of the opening 11.

In my door, neither the glass panel nor screen member has any partitions or other supports or braces visible in the opening 11 and thereby a clear unobstructed glass panel or screen in the opening 11 is provided.

When this door is used as a storm door the compartment 12 further provides an air space that serves to aid in retarding the passage of cold air to the inside.

If desired, the screen may be moved partially into the opening 11, and the other portion of the opening closed by the glass frame member, thereby making any combination of screen-glass closure desired. By the opening 11, being vertically and centrally located, a very attractive door is provided, and one that gives excellent visibility. Furthermore, air may pass into or out of the room through the screen adjacent the room floor, as well as near the ceiling of the building.

Some changes may be made in the construction and arrangement of my door without departing from the real spirit and purpose of my invention, and it is my intention to cover by my claims, any modified forms of structure or use of mechanical equivalents which may be reasonably included within their scope.

I claim:

1. In a door having an elongated vertical opening in its center, a storage area in said door at each side of said opening, a closure means capable of closing said door opening at times and also capable of residing in the storage area at one side of the opening of said door when not in use, and a second closure means having characteristics different than said first closure means; capable of closing said door opening at times and also capable of residing in the storage area at the other side of the opening of said door when not in use.

2. In a door having an opening less than one-half of its dimension in one direction, a storage area in said door at each side of said opening, a closure means capable of closing said door

opening at times and also capable of residing in the storage area at one side of the opening of said door when not in use, and a second closure means having characteristics different than said first closure means; capable of closing said door opening at times and also capable of residing in the storage area at the other side of the opening of said door when not in use.

3. In a door having an opening, a storage chamber in said door and adjacent said door opening, a second storage chamber in said door and adjacent said door opening, a screen closure capable of being positioned in said door opening at times for closing same and also capable of residing in one of said storage chambers when not in use, and a window closure capable of being positioned in said door opening at times for closing the same and also capable of residing in said other storage chamber when not in use.

4. In a door having an opening, a storage chamber in said door and adjacent said door opening, a second storage chamber in said door and adjacent said door opening and positioned opposite from said first storage chamber, a screen closure capable of being positioned in said door opening at times for closing the same and also capable of residing in one of said storage chambers when not in use, and a window closure capable of being positioned in said door opening at times for closing the same and also capable of residing in said other storage chamber when not in use.

5. In a door having an opening, a storage chamber adjacent said door opening, a second storage chamber adjacent said door opening; said storage chambers being in communication with said door openings, a track means in said door extending substantially across said opening and chambers at the upper and lower edges thereof, a screen closure slidably mounted on said track means and capable of being slid thereon from a position in one of said chambers into said door opening for closing the same, and a window closure slidably mounted on said track means and capable of being slid thereon from a position in the other said chamber into said door opening for closing the same.

6. In a door having an elongated vertical opening extending from adjacent its top center to adjacent its bottom center, a storage chamber in said door adjacent said door opening, a second storage chamber in said door adjacent said door opening, a screen closure capable of being positioned in said door opening and also capable of residing in one of said storage chambers when not in use, and a window closure capable of being positioned in said door opening and also capable of residing in said other storage chamber when not in use.
